(22) Filed: **Feb. 5, 2007**

(57) **CLAIM**

The ornamental design for a brake pedal, as shown and described.

DESCRIPTION

FIG. 1 is a perspective view showing a brake pedal of the present invention.

FIG. 2 is a front view thereof;

FIG. 3 is rear view thereof;

FIG. 4 is a top plan view thereof;

FIG. 5 is a right side view thereof;

FIG. 6 is a left side view thereof;

FIG. 7 is a partial enlarged perspective view of the section surrounding the parking brake as shown in FIG. 1

FIG. 8 is a partial enlarged front view thereof;

FIG. 9 is a partial enlarged rear view thereof;

FIG. 10 is a partial enlarged top plan view thereof;

FIG. 11 is a partial enlarged left side elevational view thereof;

FIG. 12 is a front view of a brake pedal of the present invention;

FIG. 13 is a rear view of a brake pedal of the present invention;

FIG. 14 is a top plan view of a brake pedal of the present invention; and,

FIG. 15 is a left side elevational view of a brake pedal of the present invention.

The broken lines in FIGS. 1–11 are shown for illustrative purposes only and form no part of the claimed design.
